(57) **CLAIM**

The ornamental design for a casing for illuminating device, as shown and described.

DESCRIPTION

FIG. 1 is a front elevational view of a casing for illuminating device showing my new design;

FIG. 2 is a rear elevational view thereof;

FIG. 3 is a top plan view thereof;

FIG. 4 is a bottom plan view thereof;

FIG. 5 is a left side elevational view thereof; and,

FIG. 6 is a right side elevational view thereof.

The portion shown in broken lines forms no part of the claimed design.
